Primary Examiner — Rhea Shields(57) **CLAIM**

The ornamental design for a electrical connector, as shown and described.

DESCRIPTION

1. Electrical connector

1.1 is a front view;

1.2 is a bottom view;

1.3 is a left view;

1.4 is a top view;

1.5 is a right view;

1.6 is a rear view and

1.7 is a perspective view.

In the reproductions, the broken lines are for the purpose of illustrating environment only and form no part of the claimed design.

1 Claim, 7 Drawing Sheets(56)
